HORACE L. EMERY, OF ALBANY, NEW YORK.

Letters Patent No. 88,464, dated March 30, 1869.

IMPROVEMENT IN COTTON-GINS.

The Schedule referred to in these Letters Patent and making part of the same.

To all whom it may concern:

Be it known that I, HORACE L. EMERY, of the city and county of Albany, and State of New York, have invented a certain new and useful Improvement in Cotton-Gins; and I do hereby declare that the following is a full, clear, and exact description thereof, which will enable others skilled in the art to make and use the same, reference being had to the accompanying drawings, forming part of this specification.

The nature of the invention and improvements consists of several features in the saw cotton-gin, themselves entirely simple in construction and operation, so that any farmer or planter, or ordinary hand upon the farm or plantation, can manage them with the best possible results; the whole being so complete in itself as to admit of ready and safe transportation, as well as of being operated in the open field, or under open sheds, or within the lint-room of the common gin-house, without waste of any fibres of cotton, or any more annoyance to those attending its operations than occurs in the working of the travelling grain-threshing machine.

They economize space required to operate in, and are rendered entirely free from all liability of generating fire when in operation.

By the improvements, the volume of air passing through the gin is controlled and regulated, as also the method of supplying air to the brush-cylinder is arranged so as to insure an ample supply of pure air, as also to cause its uniform distribution at all times over the whole length of the brush-cylinder and mote-board, for the purpose of insuring a more perfect and uniform separation of motes and trash from the lint, in passing the edge of the mote-board below the brush-cylinder.

Also, in the peculiar arrangement of saws and blank-disks upon the saw-shaft, in combination with the picker-roll supporter in the saw-chamber, by which the saw-gin is adapted for handling the longest and most delicate cottons known, with as little damage to their staple as by any other known device now in use.

Also, in so constructing the saw-chamber as to be readily adjusted to any size of roll, and capacity for receiving more or less, and to better handle different kinds and conditions of seed-cotton, and thereby insure the greatest efficiency in its out-turn and quality of work.

Description.

Reference is had to the accompanying drawings. Similar letters indicate like parts in the several figures.

A, Figure 1, represents the case, or frame of an ordinary saw cotton-gin.

B, fig. 1, represents the brush-cylinder in the gin.

C, fig. 1, represents the saw-shaft, with collars and saws.

D, fig. 1, represents the saws mounted on shaft C.

E, fig. 1, represents the breast of ribs or ribs forming one side of the hopper, or saw-chamber F.

F, fig. 1, represents the hopper, or saw-chamber.

G, fig. 1, represents the joint, or hinge for suspending the hopper F.

H², fig. 1, represents the picker-roll supporter mounted centrally within the saw-chamber F.

A', fig. 1, represents a flexible metallic lining to saw-chamber F.

b^x, fig. 1, represents a screw, or nut for changing the form and curvature of flexible lining A'.

J, fig. 1, represents the receiving and distributing air chamber for supplying brush-cylinder at d^x.

e e, fig. 1, represent air-openings for admission of air to the receiving-chamber J.

R, fig. 1, receiving, separating, and condensing-chamber, for receiving the discharge of air, lint, sand, dust, &c., from the brush-cylinder B.

P, fig. 1, represents an endless, or revolving screen, forming the lower, or bottom side of chamber R.

S S' S'', fig. 1, represent stripping and doffing, or delivering-cylinders, of solid material or surfaces.

q, fig. 1, represents the opening through which the air passes from chamber J to supply the brush B.

K, fig. 1, represents the ordinary movable mote-board.

Figures 2 and 4 represent plans or horizontal views of the gin and its several parts.

Figure 3 represents a vertical section of the after-portion of the cotton-gin, and of a chamber, which I contemplate making the subject of a separate patent, and, as represented, it is used without the chamber R, but forms no part of my present invention.

M, fig. 3, represents the discharge-outlet from the cotton-gin.

L, fig. 3, represents a deflecting-board, mounted on trunnions, or hinges at e', for the purpose of elevating or depressing the upper edge at f, by means of pins in the holes g g.

Figures 5 and 6 represent views of a section of the saw-shaft and saws.

D D D represent the saws mounted on shaft C.

N N N represent blank-disks mounted between the saws.

O, fig. 1, represents an extension of the gin-case, or may be made as an attachment for the safer handling and transportation, and consists simply of a chamber, R, for receiving the discharge from the gin of the wind, lint, dust, &c., in the process of ginning.

This chamber is so constructed that its bottom, or lower side, consists of an endless, or cylindrical-moving screen, P.

The motion of this screen being in the direction from the gin, constantly prevents a new field of unobstructed surface at the point nearest the brush-cylinder B, through which space or portion of screen the greater portion of the wind escapes from the chamber into the screen, and thence off through its lower portion, and at its open ends, carrying with it all dust, sand, and other foreign matter, which can pass through the screen.

The lint being lighter, floats over, and is finally ar-

rested upon the middle and after-portion of the screen, and forms a bat, or sliver, which, in the progress of the screen, is finally stripped from it, and delivered in one continuous bat at the end of the machine, by means of the solid stripping or doffing-rollers S S S', without any wind, dust, or foreign matter, coming in contact with it.

These screens may be made of brass, or galvanized iron-wire cloth, with about eight meshes to the inch, or of perforated sheet-metal, having about thirty-six holes to the square inch, and the holes to be an eighth of an inch, or so, in diameter.

The sheet-zinc, No. 9 zinc-gauge, makes a suitable covering, and is preferable to wire cloth, as it preserves the cylindrical curvature, or surface much better than wire, between the ribs which support it.

When perforated metal is used, the rough side, as left by the punching-process, should be outward and not inward, as the lint leaves the screen more easily and does not penetrate through the perforations as readily as if the smooth side were outward.

With this addition, the size of the gin is increased about fifty per cent., and yet a saving of space is the result, as several gins of the same size may be advantageously used, where only one could be used of the ordinary construction.

Again, the process of packing may be continued in the same room, without interruption or inconvenience to the attendants, more than working about a threshing-machine.

This gin is constructed with an air-chamber directly over the brush-cylinder, with ample openings on each side, right and left, for a full supply of air for the brush.

This chamber communicates with the brush-cylinder along its whole length, and quite to the point where the deflecting-board at a turns the blast from the gin.

The object and effect of this arrangement are to insure an ample and uniform supply of air to the whole surface of the brush, at the point where it is most needed; and avoid drawing its supply through below the hopper, thus insuring a much better moting below the gin, and preventing a great portion of foreign matter being drawn in and forced through the gin with the lint.

The brush-cylinders are constructed with concave heads, in the form of an annular trough, with their deepest depressions some two and a half inches, being at and around the shaft, and diminishing gradually, until the periphery is flush with the centre portion at the journals, the effect and object being to induce a strong inward current of fresh or cold air, which, in turn, is thrown off at the periphery, with great force, into the gin, and thereby preventing any accumulation of lint around the journals, to cause friction and generate fire; and, at the same time, this current of air prevents the journals and bearings from becoming heated, from ordinary causes.

The saw-chamber is provided with a false, or inside lining, of flexible, or elastic metallic plate, so mounted by adjustable screws and equivalents, as to be instantly made to conform to any degree of curvature, to better suit the capacity of the saw-chamber to the different sizes of the roll, and the various kinds and conditions of seed-cotton to be handled.

The adjustable and deflecting wind-board L, fig. 3, which, as before stated, forms no part of my present invention, placed in rear of the mote-board, is for the double purpose of deflecting the wind, or discharge from the gin, and to regulate the volume and intensity of the discharge of air from the gin, and incidentally controlling the inlet and regulating the moting along the mote-board, below the brush-cylinder.

It is mounted by hinges, or equivalents, at its lower edge, while the upper edge is raised or lowered to suit the requirements of the operator.

For ginning long-staple cotton with this saw-gin, the saws are mounted upon the saw-shaft alternately be-

tween blank-disks of a diameter a little less than the saws themselves, and the picker-roll supporter is mounted midway within the saw-chamber, and the velocity reduced to about one hundred and fifty per minute of the saw-cylinder, and the velocity of the brush-cylinder to about six hundred per minute.

By this arrangement, the roll which envelopes the picker-roll supporter can never become broken, or rope, or twisted and entangled, but at all times is revolved, in all its parts, in unison.

The saws, by this arrangement, being placed sufficiently distant from each other, the fibres cannot be seized by any two consecutive saws, nor drawn two ways at the same time, and the blanks, or disks between the saws, serving the purpose to support and move the roll, and at the same time, also, produce a complete subdivision of the surface of the cotton-roll, so as to insure the continuous rotation and presentation of that portion between any two disks to the action of the same saw, so long as the process is continued; thus never endangering the integrity of the fibre from the usual roping and twisting in the roll, nor from the double action of the saws, nor from slow speed; as, with the picker-roll supporter, any slow degree of speed may be maintained, while, without the said supporter, a high speed of the roll, to produce centrifugal suspension and propulsion of the roll, is a prerequisite to its working at all.

The picker-roll supporter, as shown at H², consists of a light, strong wood shaft, or cylinder, about two inches in diameter, and thickly studded with radial and pointed hard-wood pins, or points, about two and a half inches in length and three-eighths of an inch diameter. These are so spaced as that their points will pass between the saws, and reach nearly to the ribs between the saws.

This shaft is mounted at both ends, by means of steel shafts, or journals, about half an inch diameter, and supported by bearings in the ends of the hopper, of about two inches by two and a half inches, in an elliptical form, for the purpose of admitting an axial freedom of the journals within the bearings, and, consequently, an orbital freedom to the whole shaft, with its pointed pins.

The object and effect of this device are to support the roll in all its parts, and to move it throughout its whole length in unison, and without its depending upon the saws.

Its use prevents all clogging or bridging, and equalizes all parts of the roll, and obviates the bad results of uneven feeding by careless or inexperienced hands, and produces a uniform quality and out-turn, as, also, causes a uniform resistance to the saws at different speeds, and will admit of any degree of speed of the saws, from one up to four or five hundred revolutions per minute, as the nature of the propelling-power or the kinds and condition of the staple require.

Having thus described my invention,

What I claim as new therein, and desire to secure by Letters Patent, is—

1. A receiving-chamber attachment, or extension, for the saw cotton-gin, with its lower side, or bottom constructed of a slowly-moving endless, or cylindrical screen, having the ends of said screen open to the right and left of the gin, and its lower, or returning portion unobstructed, to permit the free escape of wind, sand, dust, and other foreign matter.

2. So placing the receiving-chamber, with its screen-bottom relatively toward the blast entering it from the gin, that this screen shall, in its movement, constantly present an unobstructed portion of its surface toward and nearest the blast as it comes from the brush-cylinder.

3. The solid doffing-cylinders, with or without flaps, in combination with a receiving-chamber of a cotton-gin, having its lower side, or bottom constructed of a

moving, or revolving screen, for the purpose of stripping the bat, or sliver from the said screen, and delivering it out from the chamber.

4. The distributing-air chamber, over the brush-cylinder, with its openings e, e , and d , as and for the purpose specified.

5. The elastic adjustable false lining in the saw-chamber of a cotton-gin, opposite the ribs and breast, for the purpose of adjusting its form and varying the capacity of the saw-chamber to the different kinds and

conditions of the seed-cotton, and to the size and density of the cotton-roll.

6. The arrangement and use of alternate saws and blanks upon the saw-cylinder of a cotton-gin, in combination with the picker-roll supporter mounted in the saw-chamber, over the saw-cylinder of a saw cotton-gin.
